UNITED STATES PATENT OFFICE.

VICTOR H. JENNINGS, OF WORCESTER, MASSACHUSETTS. ASSIGNOR TO MILLS WOVEN CARTRIDGE BELT COMPANY, OF WORCESTER, MASSACHUSETTS, A CORPORATION OF MASSACHUSETTS.

METHOD OF PRODUCING WOVEN-FABRIC RECEPTACLES.

1,130,170.

Specification of Letters Patent. Patented Mar. 2, 1915.

Original application filed June 6, 1912, Serial No. 702,034. Divided and this application filed January 5, 1914. Serial No. 310,355.

To all whom it may concern:

Be it known that I, VICTOR H. JENNINGS, a citizen of the United States, residing at Worcester, in the county of Worcester, State 5 of Massachusetts, have invented a certain new and useful Improvement in Methods of Producing Woven - Fabric Receptacles, of which the following is a specification, reference being had therein to the accompanying drawings.

The invention has relation to the art of producing receptacles in seamless pouch or bag form by the process of weaving, chiefly.

The invention consists in a novel method 15 of producing a receptacle in seamless pouch or bag form, spacing the sides apart, and shaping or squaring the ends and bottom of such receptacle, as well as reinforcing the receptacle.

20 The invention is a division of that shown and described in my application for U. S. Letters Patent filed June 6, 1912, Serial No. 702,034.

The drawings illustrate different ways in 25 which the invention may be practised.

In the drawings,—Figure 1 is an isometric view of a finished receptacle made by the practice of my novel method. Fig. 2 is a view of the said receptacle in vertical cross-section on line 2, 2, of Fig. 1. Fig. 2^a, Sheet 30 3, is a section at right angles to Fig. 2. Fig. 3 is a view in horizontal cross-section on line 3, 3, of Fig. 1. Fig. 4 is a view of the receptacle of Fig. 1, before being turned inside out. Fig. 5 is a view showing a portion 35 of the web woven for use in making receptacles like that of Figs. 1 and 4. Fig. 6 is a diagrammatic view in section of a receptacle-blank cut from the web of Fig. 5.

40 Figs. 7, 8 and 9 are views in section on lines 7, 7; 8, 8; and 9, 9, of Fig. 5. Fig. 10 is an isometric view of a slightly-modified receptacle. Fig. 11 shows a modified form of web. Fig. 12 is a diagrammatic view in 45 section of the web shown in Fig. 11. Fig. 13 is a sectional detail view of a receptacle made from the web of Fig. 11. Fig. 14 is a view in vertical section corresponding with Fig. 2, showing additional reinforcement introduced between the two layers forming the 50 double bottom of the receptacle. Fig. 15 is a view in horizontal section corresponding with Fig. 3, showing additional reinforce-

ment between the two layers of each double end of the receptacle. Figs. 16 and 17 are 55 views in horizontal section showing another way of producing a woven receptacle and its integral end reinforcements, and Figs. 18 and 19 are views in vertical section showing a woven receptacle similarly produced with 60 bottom reinforcement.

Referring first to Figs. 1, 2 and 3, the seamless woven pouch or bag-like body of the receptacle shown in such figures is squared or rectangular in cross-section. It 65 comprises a front side or face *a*, a rear side or back *b*, opposite ends *c*, *c*, and a bottom *d*. A cover or flap is shown at *e* woven in connection with the rear side *b*. Ball and socket fastenings of ordinary type are shown 70 at *f*, *g*, Fig. 1, applied to the front side *a* and the cover or flap *e*, to serve in securing the latter in place when closed down over the open top or mouth of the receptacle.

The ends *c*, *c*, are constituted by the 75 squared seamless closed end-portions of the pouch or bag. The bottom *d* is constituted by the squared seamless closed bottom-portion of said pouch or bag. At *h*, *h*, Figs. 1 and 3, are reinforcing and end-squaring 80 thicknesses in connection with the said ends *c*, *c*; and at *i*, Fig. 2, is a reinforcing and bottom-squaring thickness in connection with the said bottom *d*. The said reinforcing and squaring thicknesses space the sides 85 of the receptacle apart and give the receptacle a rectangular shape in cross-section. A receptacle embodying the features shown in Figs. 1, 2 and 3 therefore is preferable as regards appearances, and for other reasons. 90 to a receptacle having ends and a bottom which normally collapse, and which bulge or sag under the pressure or weight of the contents of the receptacle. The said receptacle is especially adapted to receive and neatly 95 and snugly fit and cover a rectangular package which just fills it.

I have shown three different ways of carrying out my invention, in each of which I produce by weaving a continuous web or 100 fabric comprising a succession of receptacle-lengths, and which continuous web or fabric I cut or divide transversely into separate blanks, each suitable for the production of a receptacle. In the first of such ways, illustrated in Figs. 5 to 9, the continuous web or 105

- fabric is woven with the openings or mouths of successive pouches or bags facing one edge of the web or fabric, and the closed bottoms thereof facing the other edge, and with the lines on which the ends of the pouches or bags are closed extending transversely of the web or fabric. The web or fabric of Figs. 5 to 9 is woven in three plies, namely a' , b' , and e' , one above another. The ply a' is for the face or front of each pouch or bag, the ply b' for the back or rear side thereof, and the ply e' for the cover or flap. The plies a' , b' , are woven together lengthwise of the web or fabric along the line a^2 , Figs. 5 and 7, adjacent one edge of the web or fabric, to form the closed bottom of a pouch or bag. They are unconnected at the opposite edge of the web or fabric, to form the opening or mouth of the pouch or bag. They are woven together transversely of the web on the lines a^3 , a^3 , Fig. 6, to close the ends of the pouch or bag. The cover or flap ply e' is connected in the weaving with the ply b' at the mouth of the pouch or bag, as shown at the left in Fig. 7, from one line of closing a^3 to the other.

To provide for the end reinforcements h , h , Figs. 1, 3, and 4, the plies a' , b' , are woven in the form of continuations h' , h' , Figs. 5 and 6, beyond the lines of closing a^3 , a^3 , the said continuations being utilized as presently will be explained. To provide for the bottom reinforcement i , Fig. 2, the plies a' , b' , are extended laterally beyond the line of union a^2 in the form of two longitudinal strips i^2 , i^2 , Figs. 5 and 7, corresponding in length to the distance between the two transverse closing lines a^3 , a^3 . The said strips are utilized as presently will be explained.

In weaving the web of Figs. 5 to 9 in a single-shuttle loom, the warp-threads and weft or filling may be interwoven as in Fig. 7, throughout the length of a pouch or bag, intermediate the lines a^3 , a^3 , Fig. 6, on which the sides of the pouch or bag are united to close the ends of the pouch or bag. In Fig. 7, the weft or filling is shown as passing from left to right through the ply a' to the point a^2 ; then passing up to the ply b' and passing to the right in the upper strip i^2 ; then passing from right to left back through said strip, and through the ply b' to the left-hand edge of the web; then passing from left to right through ply e' ; then returning from right to left through said ply e' ; then back from left to right through ply b' to point a^2 , and then in the same direction through lower strip i^2 ; then from right to left back through the said lower strip i^2 and the ply a' to the left-hand edge of the web, to a point adjacent the starting point, thereby finishing one round in the weaving. The edge of face ply a' at the mouth or opening of the pouch or bag

is a selvage edge, and so is the free or right-hand edge of the cover or flap ply e' .

In closing the ends of the pouch or bag at a^3 , a^3 , Fig. 6, warp-threads are merely crossed from ply a' to ply b' , and vice versa, as shown in Fig. 6.

In weaving the portion of web containing extensions h' , h' , the weft or filling is interwoven with the warp-threads as in Fig. 8. Starting, for instance, at point 2 at the left-hand edge of the web in Fig. 8, the weft or filling extends from left to right through the ply a' to the point a^2 ; then passing from ply a' to ply b' it extends from right to left through ply b' to the left-hand edge of the web; then it returns from left to right through ply b' to point a^2 ; then passing from ply b' to ply a' , it extends through ply a' from right to left, to a point adjacent the starting point. In order to weave the cover or flap ply e' with practically perfect selvages at both edges thereof in this portion of the web or fabric, using only a single shuttle for all three plies, the weft or filling is passed from ply b' to ply e' at the right-hand side of the web, as at a^2 , Figs 5 and 8, at intervals in the weaving of ply b' , and extends back and forth within ply e' for four or more picks, interweaving with the warp-threads of such ply to form the latter, and then returning to ply b' after, say, the fourth pick, and interweaving again with the warp-threads of the respective plies b' and a' a number of picks before again returning to ply e' . The result of this is indicated in Fig. 5, in which the connecting portions of weft or filling alternate in the selvage of ply e' with portions of such selvage which are bound by return-bends of the weft or filling woven into such ply. In this portion of the web the weft or filling does not interweave with the warp-threads pertaining to the longitudinal strips i^2 , i^2 , and such warp-threads simply float, as indicated by the dots at the right hand side in Fig. 8.

Beyond the continuations h' , h' , of the plies a' , b' , the weft or filling is interwoven with the warp-threads of the cover or flap ply e' , as shown in Fig. 9, to form that portion of the same extending between one pouch or bag and the next in the web or fabric. Ply e' is continuous, as shown in Fig. 5, and the portion of the same intermediate one pouch or bag and the next is sufficient to provide for the turning back and under of the raw or cut ends of the cover or flap against the main portion of the latter, as hereinafter explained, in finishing the cover or flap.

Between the continuations h' , h' , of plies a' , b' , at the end of one pouch-length or bag-length and the corresponding continuations at the beginning of the next length the warp-threads of the plies a' , b' , preferably float without being interwoven with weft, as shown in Figs. 5 and 9, to expedite the operation of

weaving, and avoid useless expenditure of weft or filling, inasmuch as such extensions are not required to have a length as great as the projecting end-portions of the cover or flap. Between the end of the longitudinal strips i^2 , i^2 , of one receptacle-length and the beginning of the corresponding strips of the next receptacle-length, the warps of such strips similarly float without being interwoven with weft, as in Figs. 5, 8 and 9.

The web woven as represented in Fig. 5, and containing any required number of receptacle-lengths is divided up into blanks, each of a length suitable for a receptacle, by cutting across the ply e' and the floated warp-threads of the other two plies, on the transverse lines 9, 9, Fig. 5, intermediate successive pouches or bags. A length or blank thus separated from the web is represented in longitudinal section in Fig. 6. In such blank the cover or flap is integrally joined to the top edge of the back or rear side of the receptacle from one line of union or closing a^3 to the other, and end-portions thereof project beyond the closed ends of the receptacle. These projecting end-portions are selvaged at both the upper and lower edges thereof. The short loose portions e^2 , e^2 , of weft or filling which connect the lower edges of such projecting end-portions to the lower portions of the extensions h' , h' , are cut in order to free the lower edges of the cover or flap, and are then trimmed away. The said end-portions then are folded back upon the adjoining portions of the cover or flap, the raw or cut edges are turned under, and the folded-back portions are stitched in place as shown in Figs. 1 and 4. Each end of the receptacle is finished by turning the extensions h' , h' , at such end back in opposite directions against the adjoining portions of the side-plies, and securing them to such portions by vertical and transverse lines of stitches h^2 , h^2 , h^3 , h^3 , Figs. 1 and 4. The bottom is finished by turning the strips i^2 , i^2 , back in opposite directions against the adjoining portions of the side-plies, and securing them to such portions by lines of stitches i^3 , i^3 , extending lengthwise of the receptacle, and also across the bottom near the ends of the receptacle. The lower corners are finished by transverse lines of stitches k , k , through the corner-portions of the pouch or bag and the projecting end-portions of the extensions h' , h' , and strips i^2 , i^2 . The receptacle is then in the shape and condition represented in Fig. 4, with the portions thus fastened together at the said corners projecting as shown. It is turned inside out, and the result is shown in Fig. 1. The bottom reinforce i , constituted by the longitudinal strips i^2 , i^2 , fixes the length of the receptacle, and gives shape to the receptacle at the bottom of the latter and determines the transverse diameter

thereof at the bottom, by squaring the bottom and holding the sides apart at the bottom. The corner-projections k' , k' , now turned inwardly as in Fig. 2^a contribute to keeping the width of the bottom and maintaining the shape of the lower corners. The end-reinforces h , h , constituted by the vertical end-extensions h' , h' , give shape to the receptacle at the ends of the latter, and fix the depth of the receptacle, and its internal diameter at the ends, by squaring the said ends and holding the sides apart at the ends. In consequence of the end-portions of the flap or cover being joined to the ends of the receptacle and extending half-way forward from the back, the top of the receptacle thereby is more effectually closed, and its contents better protected, when the cover or flap is turned down and secured in place. The fastenings f , g , may be applied either before or after turning the receptacle inside out.

Fig. 10 shows a receptacle modified in respect of the end-portions e^3 , e^3 , of the cover or flap e^4 . In this modification the said end-portions do not extend partway forward upon the ends of the receptacle, as in Figs. 1 and 4, but project in line with the rear side, with the extremities of such end-portions simply folded back, their cut edges turned under, and stitched in place. The cover or flap is longer than the receptacle, so that said end-portions project beyond the ends of the receptacle, to more effectually close the opening and protect the contents. In weaving the receptacle of Fig. 10, I weave the cover or flap ply joined continuously to the rear side of the receptacle only for a distance corresponding with the length of the finished receptacle, namely from point m to point m . In weaving, the web or cover or flap is woven as a distinct ply from either point m to the end of the adjacent extensions h' , h' , save for connection at intervals with the top edge of the said rear side by portions e^2 of weft or filling, at points where the weft or filling is transferred to and from the cover or flap ply in weaving portions thereof in alternation with portions in the other two plies, as already explained with reference to Figs. 5 and 8.

In the second way of carrying out my invention, illustrated in Figs. 11 and 12, the continuous web or fabric is woven with the openings or mouths of successive pouches or bags extending transversely of said web or fabric; and the closed bottoms also extending transversely thereof, with the lines on which the ends of the pouches or bags are closed extending longitudinally of the web or fabric. The web or fabric of Figs. 11 and 12 is woven in two plies, one above the other. At i^4 , i^4 , Fig. 11, the two plies constitute the reinforcing portions for the

bottom of a receptacle. Succeeding the production of such portions, the two plies are woven together at a^4 to form the line of closing or union for the bottom of the receptacle. Next the two plies are woven of sufficient extent to constitute the two sides a^5 , b^5 , of the pouch or bag of the receptacle, such plies being joined together in the weaving, along the lines a^6 , a^6 , to close the ends 10 of the said pouch or bag, and being continued laterally beyond such lines at the opposite margins of the web or fabric to form the opposite pairs of end-reinforcing strips h^5 , h^6 . The succeeding portions of the web 15 or fabric are woven to produce the cover or flap-portion e^5 , followed by the bottom-reinforcing portions i^4 , i^4 , for the next pouch or bag, and so on. The bottom-reinforcing portions i^4 , i^4 , may be woven as two 20 plies which are entirely unconnected with each other at one margin of the web or fabric, and practically unconnected at the other margin, they being merely connected at intervals by portions of weft or filling e^2 extending from one to the other, as described 25 with reference to Figs. 5 and 8. That is to say, the web or fabric being produced with one shuttle, I first weave a number of picks in one of the plies, say four, without weaving in the other ply; I then weave a corresponding number of picks in the latter ply, without weaving in the first ply; I then weave said number of picks in the first ply again, and so on. The result is that the portions i^4 , i^4 , are produced with perfect selvages at one margin of the web or fabric, and although they are joined together by the connecting portions e^2 of weft or filling 30 at intervals at the other margin, yet when such portions of weft or filling are cut and trimmed the selvages at such margin are practically as firm and perfect, and are entirely satisfactory. The line a^4 of closing or joining the sides of the pouch or bag is 35 produced merely by crossing the warp-threads, as at the lines a^3 , a^3 , in Fig. 6. The main portion of the pouch or bag may be woven as in Fig. 12, in which, starting 40 at the point 3 at the left-hand margin of the web or fabric the weft or filling extends toward the right through the lower end-reinforcing strip h^5 for the width of the said reinforcing strip. At the point 4, corresponding with one closed end of the pouch or bag, it passes up into the ply a^5 , and continues to the right in the latter to the point 45 5, corresponding with the other closed end of the pouch or bag, where it passes down, and continues to the right through the lower end-reinforcing strip h^5 at the right-hand margin of the web or fabric. It then returns from right to left through the said reinforcing strip and the lower ply b^5 to the point 4 at the left-hand end of the pouch or bag, where it passes into the upper ply 50 55 60 65

and continues through the upper reinforcing strip h^5 to the left-hand margin. Returning from left to right through the said upper reinforcing strip h^5 to the point 6, it passes down to the lower ply b^5 and continues through that to the point 7, where it passes up into the upper reinforcing strip h^5 at the right-hand side, and continues to the right-hand margin. Returning from right to left through said strip, and the upper 75 70 75 ply a^5 to the point 8, it passes down into the lower reinforcing strip h^5 at the left-hand side, and extends therethrough to the left-hand margin, thereby completing one round.

I have shown the cover or flap e^5 produced by weaving in the upper ply alone in continuation of the back side of the pouch or bag, until a sufficient length of single-ply fabric for the purposes of a cover or flap has been produced. After said cover or flap 80 85 portion has been woven, the two bottom-reinforcing plies i^4 , i^4 , for the next receptacle are woven as before, and so on. In weaving the cover or flap-portion and the said bottom-reinforcing plies a^4 , a^4 , the warp-90 threads of the end-reinforcing strips h^5 , h^5 , float as in Fig. 11, and subsequently are trimmed from the ends of said strips.

The web or fabric produced in the manner last described is divided up into receptacle-lengths or blanks by cutting across the two plies i^4 , i^4 , adjacent the end of the cover or flap-portion e^5 . A short portion of the under ply i^4 is left upon the top edge of the pouch or bag, to be folded back with its raw 100 or cut edge turned in, and stitched in place, as at e^7 in Fig. 13, to finish off the said edge. The receptacle is otherwise finished substantially as hereinbefore described. The two ends of the cover or flap portion e^5 are selvaged, and consequently do not require to be turned in to conceal raw edges as in the case of the receptacle of Figs. 1 and 4. I contemplate also weaving the cover or flap-105 portions e^5 in a flat and extended state, with 110 the warp-threads of the opposite ply floated from the top edge of the front side of the pouch or bag to the beginning of the corresponding bottom-reinforcing portion i^4 for the next pouch or bag.

Double bottoms and double end-walls such as shown in Figs. 2 and 3 may be further reinforced if desired, in accordance with one feature of the invention, by inserting between the bottom d and the two bottom-reinforcing plies i , i , lengths or strips o , o , Fig. 14, of reinforcing material of metal, vegetable fiber, etc., and by inserting similar lengths or strips p , p , Fig. 15, between the end-reinforcing plies h , h , and the end-walls c , c .

Figs. 16 and 17 show a different way of producing the woven receptacle and its integral end-reinforcements. The receptacle of these figures is woven according to well- 130

known methods of weaving pocket-webs or pouch-webs. The process of weaving is, in general terms, as follows: The receptacle is produced by weaving a multiply web or fabric with the plies unconnected along one margin to form the open mouth of the receptacle, and joined together lengthwise of the receptacle to close the bottom of the latter, the said plies being interwoven at intervals to close the ends of the receptacle. The requisite fullness of the receptacle is provided for by well-known procedure. Beyond the closed ends the weaving is continued to form end-reinforcing portions, such portions intervening between one pocket or pouch and the next in the web as produced in the loom, and being cut through transversely in severing one receptacle-blank from the rest. The result is that as shown in Fig. 16 the receptacle is woven with the end-extensions h^s , h^s , in line with or continuation of the back-wall b^s , and in this instance of greater thickness than said back-wall as a result of interweaving therein in the warp-threads of the front-wall a^s and ends c^s , c^s , in addition to those of the back-wall. In finishing the receptacle the said end-extensions are folded around against the ends c^s , c^s , as indicated in dotted lines in Fig. 16, and secured to the said ends by stitches h^{10} , h^{10} . After the bag has been turned inside out, the result is as shown in Fig. 17. The additional reinforcement of Fig. 15 may be added to the construction shown in Figs. 16 and 17, as will be obvious.

Figs. 18 and 19 show a bottom-reinforcement produced in manner similar to that in which the end-reinforcements of Figs. 16 and 17 are produced, namely, by weaving the receptacle with a bottom-extension t^s in line with continuation of one of the walls, in this instance the back wall b^s , and of greater thickness than said back wall. In finishing the receptacle the said bottom-extension is folded around against the bottom of the receptacle, as indicated in dotted lines in Fig. 18, and secured to the said bottom by stitches h^{11} . Fig. 19 shows the result after turning the receptacle inside out. The additional reinforcement of Fig. 14 may be added to the construction shown in Figs. 18 and 19.

I claim as my invention:—

1. The method of producing a woven-fabric receptacle, consisting in weaving a multiply fabric with the plies unconnected along one margin and joined together lengthwise to close the bottom of the receptacle, interweaving the said plies at intervals to close the ends of the receptacle, and beyond the closed ends continuing the weaving to form end reinforcing portions, then folding the said end-reinforcing portions laterally against adjacent portions of the fabric to form reinforcing and end-shaping

portions, and then securing these latter to the said adjacent portions.

2. The method of producing a woven-fabric receptacle, consisting in weaving a multiply fabric with the plies unconnected along one margin and joined lengthwise to close the bottom of the receptacle, interweaving the said plies at intervals to close the ends of the receptacle, and beyond the closed ends continuing the plies to form end-reinforcing portions, then folding the said end-reinforcing portions laterally against adjacent portions of the fabric to form reinforcing and end-shaping portions, and then securing these latter portions to the said adjacent portions.

3. The method of producing a woven-fabric receptacle, having a shaped and stiffened bottom, consisting in weaving a multiply fabric with the plies unconnected along one margin and joined lengthwise near the other margin to close the bottom of the receptacle and in addition form bottom-reinforcement extending from the closed bottom, interweaving the plies at intervals to close the ends of the receptacle, and then folding the bottom reinforcement laterally against the adjacent fabric and securing the same to the latter.

4. The method of producing a woven-fabric receptacle, consisting in weaving a multiply fabric with the plies unconnected along one margin and joined lengthwise near the other margin to close the bottom of the receptacle and form bottom reinforcements extending from the closed bottom, interweaving the plies at intervals to close the ends of the receptacle and beyond the closed ends continuing the plies to form end-reinforcing portions, and then folding the said bottom- and end-reinforcements laterally against adjacent portions of the fabric and securing them to said portions.

5. The method of producing a woven-fabric receptacle, consisting in conducting the weaving of a multiply fabric so as to join plies thereof together along the line of the bottom of the receptacle to close the said bottom and also so as to join them together to close the ends of the receptacle, and in addition conducting the weaving adjacent the closed ends so as to form end reinforcement extensions then folding the said extensions laterally against adjacent portions of the receptacle to reinforce and shape the ends, and then securing such end-reinforcements to the said adjacent portions.

6. The method of producing a woven-fabric receptacle consisting in conducting the weaving of a multiply fabric so as to join plies thereof together along the line of the bottom of the receptacle to close the said bottom, and in addition conducting the weaving adjacent the closed bottom so as to produce extended bottom-reinforcement, and in

- subsequently completing the receptacle folding the said bottom-reinforcement laterally and securing the same to the bottom of the receptacle to reinforce and shape the said bottom.
7. The method of producing a woven-fabric receptacle consisting in conducting the weaving of a multiply fabric so as to join plies thereof together along the line of the bottom of the receptacle to close the said bottom, and also join them at the ends of the receptacle so as to close the said ends, and in addition conducting the weaving so as to form end-reinforcement extensions and extended bottom-reinforcement, and in subsequently completing the receptacle folding the end-reinforcements and bottom-reinforcement laterally upon adjacent portions of the ends and bottom and thereby reinforcing and shaping said ends and bottom.
- 10 8. The method of producing a woven-fabric receptacle consisting in conducting the weaving of a multiply fabric so as to join plies thereof together along the line of the bottom of the receptacle to close the said bottom, and also join them at the ends of the receptacle so as to close the said ends, and in addition conducting the weaving adjacent the closed bottom so as to produce extended bottom-reinforcement, and in subsequently completing the receptacle folding the said bottom reinforcement laterally and securing the same to the bottom of the receptacle to reinforce and shape the said bottom.
- 15 9. The method of producing a woven-fabric receptacle consisting in conducting the weaving of a multiply fabric so as to join plies thereof together along the line of the bottom of the receptacle to close the said bottom, and also join them at the ends of the receptacle so as to close the said ends, and in addition conducting the weaving so as to form end-reinforcement extensions and extended bottom-reinforcement, and in subsequently completing the receptacle folding the end-reinforcements and bottom-reinforcement laterally upon adjacent portions of the ends and bottom and thereby reinforcing and shaping said ends and bottom.
- 20 10. The method of producing a woven-fabric receptacle consisting in conducting the weaving of a multiply fabric so as to join plies thereof together along the line of the bottom of the receptacle to close the said bottom, and also join them at the ends of the receptacle so as to close the said ends, and in addition conducting the weaving so as to form end-reinforcement extensions and extended bottom-reinforcement, and in subsequently completing the receptacle folding the end-reinforcements and bottom-reinforcement laterally upon adjacent portions of the ends and bottom and thereby reinforcing and shaping said ends and bottom.

fabric receptacle consisting in conducting the weaving of a multiply fabric so as to join plies thereof together along the line of the bottom of the receptacle to close the said bottom, and also join them at the ends of the receptacle so as to close the said ends, and in addition conducting the weaving so as to form end-reinforcement extensions and extended bottom-reinforcement, and in subsequently completing the receptacle folding the end-reinforcements and bottom-reinforcement laterally upon adjacent portions of the ends and bottom and thereby reinforcing and shaping said ends and bottom.

In testimony whereof I affix my signature in presence of two witnesses.

VICTOR H. JENNINGS.
